UNITED STATES PATENT OFFICE.

WILLIAM A. BELL, OF KENOSHA, WISCONSIN, ASSIGNOR TO C. M. HALL LAMP COMPANY, OF DETROIT, MICHIGAN, A CORPORATION OF MICHIGAN.

LAMP RING.

1,422,525.

Specification of Letters Patent. Patented July 11, 1922.

Application filed July 29, 1920. Serial No. 399,845.

To all whom it may concern:

Be it known that I, WILLIAM A. BELL, a citizen of the United States, residing at Kenosha, in the county of Kenosha and State of Wisconsin, have invented certain new and useful Improvements in Lamp Rings, of which the following is a specification.

My invention relates to improvements in lamp rings, and especially has reference to devices for locking in position the glazings of lamps such as may be used on self-propelled vehicles.

The principal objects of the invention are — to provide an improved ring of the class described, which may be conveniently utilized in connection with devices for sealing the interior of the lamp against ingress of moisture, dirt, or deleterious gases; to provide an improved arrangement of the class described which may readily be employed in connection with existing designs of vehicle lamps; to provide an improved arrangement whereby the ring may be readily removed to permit removal of the lamp glazing when access to the interior of the lamp is desired; to provide an arrangement so organized that the ring may be securely clamped in position by manipulating a single locking member; to provide an improved arrangement which will conform to the ornamental lines of the lamp without detracting from the appearance thereof; to provide a construction which shall be simple and economical in design and manufacture, and efficient in use; and, in general, to provide an improved lamp ring of the character referred to.

In the drawings, which illustrate my invention as applied to an automobile head-lamp—

Fig. 1 is a partial axial or vertical section showing the lamp in elevation;

Fig. 2 is a front elevation of the lamp shown in Fig. 1, certain parts being broken away the better to illustrate the mechanical construction; and

Fig. 3 is a section taken on the line 3—3 of Fig. 2.

Referring to the drawings, it will be observed that the lamp is constructed with a main outer casing 10 having an inner parabolic reflector 11 forming a cavity or recess 12 in which is enclosed an electrical lamp bulb 13 having a filament 14 suitably placed

at, or adjacent to, the focus of the parabolic reflector 11.

In the particular lamp shown and described, the main body or casing 10 is made with a lower subsidiary casing portion 15 which encloses a minor parabolic, or other shaped, reflector 16 enclosing a lamp 17 which is of less candle-power than the lamp 13 and is used in place of the main headlamp when the car is standing or when driving through city streets which are reasonably well illuminated. The upper glazing 18 constitutes a closure for the front of the recess 12, and the lower glazing 19 serves the same purpose with reference to the lower or minor recess 20 formed by the reflector 16. 70

The main reflector 11, as shown in the drawings, is formed with a circular edge bead 21 from which projects an annular flat flange 22, between which and the glazing 18 there is interposed a gasket 23 constructed of rather flexible material, such as heavy paper board. To the outer edge of the stamped sheet metal body or casing 10 there is suitably united an annular stamped metal border frame portion 24, said union preferably being facilitated by suitably shaped interlocking flanges 25 and 26 formed respectively on the main body 10 and the said border frame 24.

The border frame portion 24 is made with an intermediate forwardly-facing part 27, the inner edge of which is bent inwardly, as shown at 28, to constitute a circular recess which is of large enough diameter to receive freely the flange 22 of the reflector, the gasket 23, the glazing 18, and the ring 29. The inner end of said cylindrical flange 28 is bent at right-angles, as shown at 30, in order to form a flat annular terminal flange portion located behind the reflector flange 22, 95 and on said flat rear flange 30 there are secured by suitable means, such as rivets 31, a plurality of plate springs 32. Each of said springs 32 is made with oppositely located circumferentially-extending spring arms 33 100 which lie behind the reflector flange 22, engage the latter, and tend to force the reflector out of the lamp. The said springs 32 thus serve to clamp the gasket 23, glazing 18, and reflector flange 22 tightly in sealing engagement so that the reflector cavity 12 is rendered gas-tight and moisture-proof. 105

The locking ring 29 obviously serves to

locate the glazing 18, operating as a stop to limit the outward movement of the parts acted upon by the resilient members 32, said locking ring 29 constituting one of the 5 principal features of my invention.

The means for locking said ring 29 in position in the lamp frame comprises, in the present instance, interlocking members carried respectively by the frame and the ring, 10 the locking members being disengageable so that the lamp ring may be removed from its frame whenever it is desired to gain access to the interior of the illuminant cavity 12. Preferably, I employ a plurality of sets of 15 such interlocking members. In the case of the major headlamp 10 I have shown three sets of locking members, and in the case of the lower casing, I have indicated only two sets of interlocking members. It will be observed, however, that the principle employed 20 is somewhat similar in the case of each lamp.

In the present instance, in connection with the main locking ring 29 I have shown two sets of upper interlocking means which are 25 non-adjustable, and a lower interlocking means which may be adjusted or disengaged to release the locking ring at the point where said adjustable interlocking member is located,—in the present instance, at the bottom 30 of the ring. The releasing of the bottom of the ring enables the lower portion thereof to be shifted outwardly of the lamp, and the two upper sets of interlocking means are so located that after the lower end of the ring 35 has been pulled away from the recess, the ring itself may be lowered vertically to release the upper locking members, after which the ring is free to be moved bodily outwardly away from the lamp, permitting removal of 40 the glazing.

It will be observed that when the lower part of the ring 29 is pulled outwardly in order to free same from the lamp frame, the upper end has a tendency to move inwardly, 45 due to the locking ring member functioning as a lever pivoted upon the two points of support represented by the upper interlocking members. Such inward movement of the top portion of the ring is of course permitted 50 by reason of the resiliency of the springs 32, which preferably, in order not to interfere with such movement, may be located adjacent to, or slightly below, the fixed interlocking members.

55 As to the fixed interlocking members, these may comprise small metal stampings 34 having inwardly-bent lugs 35 extending through the cylindrical flange 28 a sufficient distance to enter slots 36 punched through 60 the cylindrical outer wall 37 of the hollow locking ring 29. It may be observed in passing that the said hollow locking ring 29 is made with a curved annular flange 38 conforming to the general design of the lamp 65 and having its inner end engaging the front

of the glazing 18. As observed in Fig. 2, the slots 36 are of sufficient circumferential length to permit the lugs 35 to be disengaged when the lamp ring is shifted laterally or downwardly towards the adjustable locking 70 point.

The adjustable locking member may consist of a rotary catch 39 keyed to a horizontal pin or screw 40, the head 41 of which is exposed at the front of the lamp frame and is 75 slotted to enable the said pin 40 and catch 39 to be rotated by a screw-driver or similar tool. The catch proper 39 comprises a suitable stamped washer-like part having a portion of one of its sides cut away so that when 80 the pin 40 is turned to the proper position, the locking ring at that point is released. Under normal conditions, the catch is in the position shown in Fig. 2, in which position the circular portion of the washer extends 85 through a slot 42 cut in the cylindrical flange 28, and also into a slot 43 punched in the cylindrical flange of the removable locking ring 29.

It will be observed that the lower casing 90 for the minor lamp 17 is constructed along substantially the same lines as the upper or major casing, and that the catch member 39 cooperates with the upper part of the minor locking ring 44 in the same manner in which 95 the catch cooperates with the upper locking ring 29. As shown, the ring 44 has an equivalent cylindrical portion 37^a, to which is united an upper lug 45 perforated to admit the catch 39. On the lower part of said 100 ring 44 there is also united an angular lug 46 which is arranged to enter an aperture 47 punched in the cylindrical wall of the lower glazing recess. The lower ring 44, however, being of relatively small diameter, I have not 105 found it necessary to use more than a single set of fixed or rigid interlocking members for the opposite side of the ring, and also only a single pair of springs 55 need be employed. 110

The described details of construction are merely illustrative of a single phase of my invention, the scope of which should be determined by reference to the appended claims, said claims being interpreted as 115 broadly as possible consistent with the state of the art.

I claim—

1. The combination of a lamp casing member, a glazing constituting a front closure for said casing, a locking ring member insertable in said casing over the glazing, and means for retaining said ring in the casing comprising a plurality of locking means respectively located on opposite sides 120 of the casing, each of said locking means comprising a lug and an opening therefor respectively provided on said members, one of said lugs being shiftable to permit insertion or removal of the ring, 125 130

2. In combination, a lamp casing member provided with an annular recess surrounding the opening, a glazing in said recess constituting a closure for the casing, a locking ring member insertable in said recess over said glazing and fitting said recess and means for retaining said ring in said recess comprising a plurality of locking means respectively located on opposite sides of the 10 diameter of the recess, each of said locking means comprising a lug and an opening therefor respectively provided on the said members, one of said lugs being shiftable to permit insertion or removal of the ring.
- 15 3. In combination, a lamp casing member provided with an annular recess surrounding the opening, a glazing in said recess constituting a closure for the casing, a locking ring member insertable in said recess over 20 said glazing and fitting said recess and means for retaining said ring in said recess comprising a pair of locking means respectively located on opposite sides of the diameter of the recess, each of said locking means 25 comprising a lug and an opening therefor respectively provided on the said members, one of said lugs being shiftable to permit insertion or removal of the ring, the casing being provided at the bottom of the recess with an inturned flange having resilient 30 means interposed between the glazing and said flange for holding the glazing in contact with the ring.
4. In combination, a bowl-shaped lamp casing provided at its front end with a cylindric reentrant flange member, said flange having at its inner end an inturned flange and a substantially rigid locking ring member insertable within said cylindric flange member, means for retaining said ring in 35 the recess formed by said cylindric flange member comprising a pair of locking means located on opposite sides of the diameter of the ring, each of said locking means comprising a lug and an opening therefor 40 respectively provided on said members, a glazing insertable in said recess and engaging said ring, a reflector located in the casing and having an outer circumferential flange in the recess to overlap said inturned 45 flange and resilient means interposed between the reflector flange and the inturned flange for forcing said reflector and said glazing against said ring, one of said lugs being shiftable with reference to its opening, to permit insertion or removal of the 50 ring.
- 55

WILLIAM A. BELL.
